GARMENT POCKET

Irving M. Falk, Philadelphia, Pa., assignor to Nu
Pocket Method Company, Philadelphia, Pa.

Application August 16, 1948, Serial No. 44,465

1 Claim. (Cl. 2-247)

1 My invention relates to a new and useful garment pocket and has for one of its objects to so construct and assemble the pocket in a garment that some of the ordinary operations are eliminated and a clean, neat and strong structural item results from the combination of parts.

Another object of the invention is to provide a pocket construction particularly adapted for use as a side or front pocket in a pair of trousers.

Another object of the present invention is to provide a unique way of enclosing the raw edges of a pocket seam and a portion of a garment seam adjacent the line of attachment of the pocket to the garment to give a neat appearance to the assembly and a clean ravel-free pocket insides.

A further object of this invention is to provide improved means for hanging one side edge of a pocket to a garment whereby greater support is provided without causing a sagging effect to the garment in the region of the location of a pocket.

A still further object of the invention is to utilize a new method of attaching a pocket to a garment, such as a pair of trousers.

With the above and other objects in view this invention consists of the details of construction and combination of elements herein-after set forth and then designated by the claim.

In order that those skilled in the art to which this invention appertains may understand how to make and use the same I will describe its construction in detail referring by numerals to the accompanying drawings forming a part hereof, in which:

Fig. 1 is an outside face view of the upper part of a pair of trousers illustrating the relation of the side pocket to the other parts and showing one form of pocket opening.

Fig. 2 is a fragmentary inside view thereof in the region of the side pocket which is partly broken away and the tape turned back.

Fig. 3 is a section on the line 3-3 of Fig. 2.

Fig. 4 is a section on the line 4-4 of Fig. 2 with all parts secured in place.

Fig. 5 is an outside face view of the upper part of a pair of trousers opposite to that shown in Fig. 1 and illustrating another type of pocket opening.

Fig. 6 is an enlarged section at about the line 6-6 of Fig. 5 with the pocket turned inside out as the elements are stitched during the preliminary steps of the assembly.

Fig. 7 is a similar section after completion of

the formation of the pocket and turned right side in.

Fig. 8 is an enlarged section at the line 8-8 of Fig. 5.

In carrying out my invention as herein embodied 10 represents a garment, such as a pair of trousers, including front and rear sections of the garment material 11 and 12, respectively, sewn together and forming a seam 13. By leaving a portion of the seam unstitched near the top a pocket opening 14 is provided. In the formation of the pocket opening, a triangular area 15 of the front garment material section 11 is folded in to provide an inclined edge 16, Fig. 1, for the pocket opening. If the turned in area of said front garment material section 11, in the region of the pocket opening, is folded in evenly a straight edge 17, is provided.

As shown in Figs. 1 to 4, inclusive, the pocket 18 is formed by folding a piece of pocket material upon itself and sewing the upper portion of the outer panel 19 to the garment section 11 between the main part and turned in area of said garment section 11 by the stitches 20.

25 The inner edge of a facing strip 21 is stitched to the inside surface of the pocket panel 22 by stitches 23. A hanger strip 24 has an edge folded into the contiguous edge of the garment section 12 and said folded portions and the outer edge of the facing strip 21 are sewn together by stitches 25 in a single operation.

Finally a binding tape 26 is folded in U-shape and assembled to embrace and inclose the coinciding edges of the bottom and lower portion 35 of the side of the pocket, as in Figs. 2 and 3, and then the upper portion of the edge of the inner panel 22 of the pocket and the inner edge of the hanger strip 24 are enclosed in the binding tape, as in Figs. 2 and 4, and the parts are sewn together by two parallel rows of stitches 27, Fig. 2, one row only passing through the binding tape. Thus the pocket below the pocket opening and its attachment to the hanger strip is accomplished in one operation.

40 In that form of structure illustrated in Figs. 5, 6 and 7, a facing strip 28 is sewn along its inner longitudinal edge by stitches 31 to the side edge of the inner panel 29 of the pocket 30 in back to back relation while the pocket material is turned inside out. Then the facing strip is folded to project outwardly from its sewn edge in a plane substantially parallel to the pocket panel 29. Also a hanger strip 32 is sewn along its inner longitudinal edge by stitches 33 to the side edge of the pocket panel 33 in

Fig. 7 is a similar section after completion of

back to back relation while the pocket material is turned inside out and then said hanger strip 32 is stretched out so as to be in the same plane as said pocket panel 33, as shown in Fig. 6.

Next, the other longitudinal edge of the hanger strip 32 is sewn to the edge of the garment section 11 in the region of the pocket opening by stitches 35 while the parts are in back to back relation. The hanger strip 32 and the garment section 11 are then stretched out so as to lie in substantially the same plane. Thereafter, the other longitudinal edge of the facing strip 28 is sewn to the edge of the other garment section 12 in the region of the pocket opening by stitches 36 while the parts are in face to face relation.

The bottom and side edges of the pocket material below the pocket opening are still unattached but said pocket material is now turned right side in and closed by folding a piece of binding tape 37 generally U-shaped and assembling said tape to embrace and enclose the coinciding bottom and side edges of the pocket material below the pocket opening and the stitched edges of the facing strip and garment section 12 in the region of said pocket opening. The binding tape 37 is sewn in place by the stitches 38 in the same manner as shown in Fig. 2.

In every instance, the end of the binding tape 37 along the bottom of the pocket originally extends past the fold of the pocket and this projecting end is folded in, as at 39, Fig. 8, to be positioned between the pocket and the contiguous garment material and said folded end of the tape is tacked in place by stitches 40.

From the foregoing it will be apparent that I have provided a simple construction of garment pocket which is not only neat in appearance and has a clean smooth interior surface, free of ravelings, but also one in which the area thereof adjacent its connection with the rear garment section 12, where the greatest strain occurs, is suspended by the hanger strip away from the garment section edge to thereby reinforce the connection between the garment and pocket.

Of course I do not wish to be limited to the exact details of construction herein shown and

described as these may be varied within the scope of the appended claim without departing from the spirit of my invention.

Having described my invention what I claim as new and useful is:

In a garment pocket, front and rear garment sections sewn together throughout the major portions of their lengths forming a seam and being free above the seam to form a pocket opening, the free edge of the front garment section folded inward at an angle to produce an inclined turned edge, a strip of pocket material folded upon itself on a vertical line to provide outer and inner panels and disposed in the garment with the upper portion of said outer panel between the main and inturned parts of said front garment section and sewn in place, a facing strip and a hanger strip sewn to the free edge of the rear garment section, and said hanger strip sewn to the edge of the inner pocket panel and said facing strip sewn to said inner pocket panel an appreciable distance from the hanger strip and disposed to cover the latter, and a binding tape enclosing the edges of both pocket panels along the bottoms and side to the pocket opening of the garment and the coinciding edges of the hanger strip and inner panel of the pocket.

IRVING M. FALK.
